(57) **CLAIM**

The ornamental design for a faucet mount housing, as shown and described.

DESCRIPTION

FIG. 1 is a perspective view of a faucet mount housing illustrating our new design;

FIG. 2 is a front side elevational view of the design of FIG. 1; FIG. 3 is a back side elevational view of the design of FIG. 1; FIG. 4 is a left side elevational view of the design of FIG. 1; FIG. 5 is a right side elevational view of the design of FIG. 1; FIG. 6 is a top planar view of the design of FIG. 1; and, FIG. 7 is a bottom planar view of the design of FIG. 1.

In the drawings, the broken lines depict environmental subject matter only and form no part of the claimed design.
